APPARATUS FOR CLEANING TANKS AND
THE LIKE

Clare Richard, Los Angeles, and Harold M. Ruth,
Huntington Park, Calif., assignors, by direct
and mesne assignments, to The Pyrate Cor-
poration of Nevada, a corporation of Nevada

Application October 10, 1932, Serial No. 637,028

11 Claims. (Cl. 299—73)

This invention has to do in a general way with devices for washing the interior of tanks, and is more particularly related to devices of the class described which are especially adapted for use in washing the interior of tank cars.

It is well known to those familiar with the art that it is necessary to clean tank cars periodically, and there are various features connected with the washing of the interior of these tanks which requires special equipment. In the first place the tanks may have contained gasoline or some other liquid, the vapors of which are inflammable and toxic. It is, therefore, necessary that the apparatus employed be such that it does not require an operator at a point where he is exposed to the fumes or vapors driven from the tank while the washing apparatus is in operation.

In recent practice attempts have been made to wash tank cars by means of a spray or nozzle which is lowered into the car through the manhole, the supporting means for the nozzle being constructed so that it may be moved for directing the spray into various positions in the car. One such type of apparatus is constructed so as to be manually operated from above the car. Such a device is most unsatisfactory, due to the fact that the operator is continuously exposed to the vapors and fumes coming from the car during the washing process, and further due to the fact that the device will not systematically and thoroughly wash every part of the tank. The use of a motor for turning the spray is unsatisfactory due to the limited space in which the device must be installed and operated. It is, therefore, a primary object of this invention to produce a device of the class described in which the washing stream or spray is projected into the car from a rotatable nozzle, such nozzle being adapted to rotate in a substantially vertical plane and associated with means for turning the nozzle bodily during its rotation about a vertical axis, such turning movement being automatically effected by the rotation of the nozzle.

It is well known to those familiar with the art that the tank on a tank car is provided with a dome having a manhole, and it is through this manhole that the apparatus, contemplated by this invention, is lowered and supported in the tank. In view of the fact that the tanks may vary in diameter and the domes may vary in height, it becomes a further object of this invention to produce a nozzle support which is vertically adjustable and may be locked in various positions of vertical adjustment.

As was pointed out above, the nozzle unit, contemplated by this invention, rotates in a vertical plane and turns about a vertical axis, and further that the unit is suspended through the dome. In view of this construction it will be seen that the periphery of the dome itself may not receive a thorough washing action, and since this surface is the only surface in the car which is not directly exposed to the spray in the device of our invention, it is a further object of this invention to provide the device with a deflecting member arranged so as to direct a portion of the vertically directed stream angularly into the dome and against the interior surface thereof.

The device of this invention is provided with a cover plate for the manhole which has clamping means adapted for use on manholes of various diameter and with manhole flanges of various widths.

The cover plate also has an opening to provide a vent for the escape for the vapors and fumes, such opening being associated with baffle means to prevent the throwing of the washing liquid from the tank as the nozzles traverse their vertical positions.

Another important feature of this invention resides in the provision of visible means for indicating, at a point above the tank, the rotation of the nozzle about its axis and the rotation of the nozzle unit about the vertical axis.

The general construction of the device contemplated by this invention comprises a cover plate adapted to fit over the manhole of the tank, such cover plate being provided with an opening and means therein for supporting a vertical conduit or pipe. This pipe or conduit is provided with a thrust bearing which supports, what we may term, a sleeve, the lower end of which has an angular nozzle feed pipe which feeds liquid to and acts as a bearing for a rotatable nozzle unit. The nozzle unit is associated with means for holding same upon its bearing.

It is a further feature of this invention that the thrust bearing is positioned inside of the tank so that the tank receives any liquid which may leak through the bearing.

The details in the construction of a preferred form of our invention, together with other objects attending its production, will be best understood from the following description of the accompanying drawings which are chosen for illustrative purposes only, and in which—

Fig. 1 is an elevational view of a tank car showing a preferred form of our invention mounted therein;

Fig. 2 is an elevational view with parts broken away illustrating the details in the construction of a preferred form of our invention;

Fig. 3 is a plan section taken in a plane represented by the line 3—3 in Fig. 2;

Fig. 4 is a partial elevation which may be considered as having been taken in the direction of the arrow 4 in Fig. 2;

Fig. 5 is a fragmentary section taken in a plane represented by the line 5—5 in Fig. 4;

Fig. 6 is a sectional elevation taken in a plane represented by the line 6—6 in Fig. 5;

Fig. 7 is a fragmentary elevation which may be considered as having been taken in the direction of the arrow 7 in Fig. 2;

Fig. 11 is a plan section taken in a plane represented by the line 11—11 in Fig. 2;

Fig. 12 is an elevational view with parts broken away showing a modified form of our invention;

Fig. 13 is a fragmentary elevational view with parts broken away which may be considered as having been taken in the direction of the arrow 13 in Fig. 12; and

Fig. 14 is an inverted plan view taken in a plane represented by the line 14—14 in Fig. 13.

More particularly describing the invention as herein illustrated, reference letter A indicates a tank car having a tank B provided with a dome C through the manhole of which a cleaning or washing device D is suspended. As will be seen from Fig. 2, the dome C has a manhole E which is provided with a downwardly extending flange F. In addition to the dome the tank is provided with an opening G through which the wash liquid drains from the tank.

Reference numeral 11 indicates a cover plate or cover member which is mounted over the manhole E, which is provided with the central opening 12, and a peripheral flange 13. The flange 13 is provided to prevent any liquid which may leak from parts above the cover from running on to the outer surface of the dome or tank, such liquid being directed into the tank through the opening 12.

Reference numeral 14 indicates web plates which are mounted on the cover plate 11 forming a spider which supports a split collar member 15. The split collar member 15 is provided along its division line with outwardly extending flanges 16, such flanges forming the bearing for the pin 17 which supports a pinion gear 18 and is provided on its extending end with a crank 19.

60 The pinion gear 18 engages rack teeth 20 on the periphery of a main feed pipe on fixed conduit 21. This main feed pipe or fixed conduit is provided on its upper end with a T-connection 22 which receives a hose or any other suitable type of conduit 23 for delivering a wash liquid into the main feed pipe.

70 It will be apparent from the construction so far described that the means of supporting the main feed conduit in the split collar 15 permits vertical adjustment of the main feed conduit and its associated parts, and for the purpose of clamping the split collar on the main feed conduit for locking the latter in various fixed positions of adjustment we provide a bolt or another 75 suitable member indicated at 22' which extends

through one of the flanges 16 and is threaded into the other.

The lower end portion of the main feed conduit 21 is provided with, what we may term, a bearing flange 25, such flange forming a race for 5 roller bearings 26 which support a collar 27 threaded in the upper end of a bell 28 formed on the upper end of a sleeve member or rotatable conduit section 29.

The section 29 is shown as being formed in 10 two parts threaded together and carries at its lower end a T-member 30. One opening of the T-member 30 receives a nozzle feed pipe 31. This nozzle feed pipe constitutes a bearing for the hub portion 32 of a nozzle member 33. In 15 this form of our invention, the nozzle member 33 consists of two diametrically disposed nozzles 33a and 33b, such nozzles having tips 34a and 34b arranged so as to eject their streams at an angle for rotating the nozzle member upon the 20 hub in the general direction of the arrow N. The nozzle member is secured upon the nozzle feed pipe by means of a bushing or cap 35, and the feed pipe is provided with a plurality of apertures 36 situated in the plane of rotation of the 25 nozzles, the hub of the nozzle member being provided with an annular channel 37 so that the nozzles are at all times in internal communication with the apertures in the nozzle feed pipe.

From the construction so far described it will 30 be seen that when a washing liquid, such as water under pressure, is delivered into the main feed pipe 21 through the connection 23 and the T-member 22, that such liquid will be delivered to the nozzle member 33 and that the ejection of 35 such liquid will effect a rotation of the nozzle member.

It was pointed out as a primary object of this invention to provide a device of the class described which utilizes the rotation of the nozzle member about a substantially horizontal axis for the purpose of turning the nozzle member as a unit about a vertical axis. In this form of our invention the rotation of the nozzle member as a unit about a vertical axis is effected by 45 turning the sleeve member or rotatable conduit section on the bearings 26.

The means for effecting such turning movement consist of a shaft 40 which extends through a packing nut 41 in one end of the T-member 30 50 and through the bushing or cap 35 which holds the nozzle hub on the nozzle feed pipe. The end 42 of the shaft which extends through the cap 35 is bent so as to lie in the path of rotation of the nozzle member 33, thus during the rotation of 55 the nozzle member 33 the shaft 40 is rotated correspondingly. The end 43 of the shaft 40, which extends through the packing nut 41, is formed or provided with an eccentric which is received in a collar 45 attached to a pitman rod 46. The 60 upper end of the pitman rod is bent so as to extend through the end 47 of a bell crank 48 which is pivotally mounted upon a bracket 49 formed or mounted on the upper end portion of the sleeve member or rotatable conduit section 29.

Reference numeral 50 indicates a ratchet wheel which is rigidly mounted upon the fixed conduit section or the main feed pipe 21. The ratchet wheel 50 is provided with ratchet teeth 51 and such teeth are adapted to be engaged by 70 the upright finger 47' on the bell crank 48. The bell crank 48 is supported on the bracket so as to have a yieldable outward movement which is permitted by the coil spring 52.

It will be seen that as the shaft 40 is rotated 75

5 by the nozzle member 33 the pitman rod 46 receives a reciprocating motion which is imparted to the bell crank 48. Since the ratchet wheel 50 is rigid and the bell crank is supported on a structure which is rotatable relative to the ratchet wheel, this swinging movement of the bell crank results in a step by step turning motion being imparted to the sleeve member or rotatable conduit section 29 through bracket 49. This action 10 is indicated by the dotted line positions of the bell crank and the bracket 49 as shown in Figs. 7 and 8.

15 It was pointed out in the early part of the specification as one of the objects of this invention to provide means for indicating both the rotation of the nozzle member and the turning motion of the sleeve member or rotatable conduit section at a visible point above the tank. Such indication in this form of our invention is 20 obtained by providing the shaft 40 with an eccentric section 55 situated substantially on the axis of the vertical conduit formed of sections 21 and 29. The eccentric portion 55 is received in a collar 56 which is attached to the lower end 25 of the rod 57 which extends upwardly through the vertical conduit and has its upper end projected through a packing gland 58 where it is provided with a needle or other suitable indicator 59.

30 As the shaft 40 is rotated directly from the nozzle the rod 57 is reciprocated once for each rotation of the nozzle and inasmuch as the rod is directly connected to the shaft, it will be seen that the rod, in addition to this reciprocating motion, is rotated directly with the sleeve member, thus the speed of the rotation of the upper end of the rod 57 indicates the speed at which the nozzle unit is being turned about a vertical axis and the speed of reciprocation indicates the 35 speed of rotation of the nozzle about the nozzle feed pipe.

35 As was pointed out above, means are provided on the device, contemplated by this invention, for automatically governing the speed of operation 40 of the nozzle. Such speed governing means in this form of our invention are best illustrated in Figs. 2, 4, 5, 6 and comprise a sprocket wheel 60 which is mounted on the nozzle hub and which drives a sprocket chain 61, which, in turn, drives 45 a sprocket pully 62 mounted on, what we may term, a governor shaft 63.

50 The governor shaft 63 is supported in a bearing 64 which is formed on a collar 65 mounted on the rotatable conduit section 29'. The opposite end of the governor shaft 63 is threaded as indicated at 65'.

55 Reference numeral 66 indicates a diamond nut mounted on the threaded portion 65' in close proximity to the end of the shaft bearing 64. This nut is adjusted so that a slight rotation 60 thereof in the threaded portion 65' will bring the same into engagement with the face of the bearing member and thus retard the speed of rotation of all parts associated with the shaft 64.

65 For the purpose of controlling the movement of the diamond nut 66 with the speed of rotation, we provide a governor plate 67 which is threaded on the shaft 65' and is locked in proper position thereon by means of a lock nut 68. The 70 diametrically opposite ends of this governor plate 67 are bent inwardly as indicated at 69 and 69' to form bearing ears or flanges which are provided with apertures for the reception of guide pins 70 and 70' formed on the outer ends of weight members 71 and 71' respectively which

5 extend through apertures 73 and 73' on opposite ends of the diamond nut 66. Compression springs 75 and 75' are interposed between the end flanges 69 and 69' and the outer ends of the respective weight members 71 and 71'. It will thus be seen that during the rotation of the governor plate 67 by the sprocket wheel 62, the centrifugal action will throw the weights outwardly against the action of the compression springs and when a predetermined speed has been 10 reached the centrifugal force is sufficient to overcome the force of the springs to such an extent that the diamond nut 66 is rotated into engagement with the bearing, thus retarding the movement of the associated parts. As the movement is retarded the springs force the weights toward the center and the nut is rotated away from the bearing so that the governor provides a simple and accurate means for controlling the 15 speed of the operation of the unit.

20 Reference numeral 76 indicates a bore hole which may be provided in the bearing and in the conduit section 29' to permit water lubrication of the shaft 63 if so desired.

25 Reference numeral 78 indicates a guard member which is mounted on the rotating member to protect the governor and the pitman bar.

30 In order that we may provide ample ventilation through the cover plate and at the same time prevent the spray being thrown therefrom as the nozzles traverse their vertical positions, we provide, what may be termed, a baffle plate 80 which is mounted on the collar member in 35 downwardly spaced relation with the opening 12.

35 Reference numeral 81 indicates nipples which are provided with caps 82 and which may be used for the purpose of delivering steam or other fluid into the tank when the unit is installed.

40 For the purpose of making the cover member adaptable for various sizes and types of manholes, we provide a novel form of clamping means generally indicated by reference numeral 84, such clamping means comprising a plurality of threaded collars 85 formed on the cover member, such collars receiving threaded pins 86, the lower ends 45 of such pins being provided with tapered wings 87 which are adapted to engage the flange F. The pins are advanced into clamping engagement with the threaded portion by wing nuts indicated at 88.

50 Reference numeral 89 indicates a conical deflecting member which is mounted on the fixed conduit section in a position above the path of the nozzle member when it is traversing a vertical plane so that a part of the spray coming from 55 the nozzle as it is projected upwardly is deflected angularly into the dome C so as to thoroughly wash the inner wall of the dome.

55 In Figs. 12 to 14 inclusive I show a modified form of construction which is designed to operate 60 in the same general way as the construction just described but in which the means for turning the rotatable pipe section about its axis are slightly different from those described above. In this form of our invention the cover member, the baffle 65 plate and the clamping means are all the same as those described in connection with Fig. 2. The collar member 100 and the fixed pipe section 101, however, in this form of our invention are not shown as being provided with the vertical adjustment, although, such adjustment could obviously be used in connection with this type of apparatus.

70 The upper end of the fixed section 101 is provided with a T-connection 102 for receiving wash- 75

ing liquid. The lower end is provided with a thrust bearing indicated at 103 which is the same as the bearing shown in Fig. 2 which supports a rotatable pipe section generally indicated by reference numeral 104. The lower end of the rotatable pipe section carries an angularly disposed nozzle feed pipe 105 upon which a nozzle 106, similar to the nozzle member 33, is rotatably supported.

10 The hub portion of the nozzle member 106 carries a beveled gear 107 which engages a beveled gear 108 mounted on the lower end of a pin or shaft 109 which is shown as extending axially through the vertical conduit section and through 15 a packing gland 111 in the T-member 102. The shaft 109 is free to rotate relative to the conduit and is supported therein in any suitable manner such as by means of a bearing collar 109'. The beveled gear 108 is formed with or keyed to a spur 20 gear 112 which engages another spur gear 113 mounted on the lower end of the shaft 114 which is supported in bearings 115 and 116, such bearings being supported from the rotatable conduit section 104 by means of brackets 114' and 115'. 25 The shaft 114 is provided on its upper end with an eccentric 117 which carries a pawl member 118, such pawl member being pressed into yieldable engagement with teeth 120 on a ratchet wheel 121 by means of a tension spring 122. The 30 ratchet wheel 121, like the corresponding wheel 58 in Fig. 2, is rigidly secured on the fixed conduit section 101. It will be seen from this construction that during the rotation of the nozzle member 106, the shaft 114 receives a corresponding 35 rotation which, through the eccentric 117, reciprocates the pawl relative to the ratchet wheel and imparts a step by step turning movement to the rotatable conduit section 104. The upper end portion of the shaft 109 provides an indicator for 40 indicating the speed of this last mentioned rotative movement.

Reference numeral 125 indicates a governor which is similar in operation to the governor shown and described in connection with Figs. 2, 4, 45 5, and 6.

It will be apparent from the foregoing description that the device contemplated by this invention is of simple form and construction; it is entirely automatic in its operation; it provides ample ventilation for the tank without spillage over 50 the outside of the tank; it is constructed so as to thoroughly cleanse all points on the interior surface of the tank and the tank dome; it may be readily adjusted for speed of operation; and is 55 adapted for use on tanks and domes of various sizes and constructions.

It is to be understood that, while we have herein described and illustrated certain preferred forms of our invention, the invention is not limited to the precise construction described above but includes within its scope whatever changes fairly come within the spirit of the appended claims.

We claim as our invention:

65 1. A device for cleaning tanks and the like embodying: a conduit; means for suspending said conduit on a substantially vertical axis; a reaction nozzle member mounted on said conduit for rotation about a horizontal axis; and means 70 operated by the rotation of said nozzle member for imparting one step of rotation to said conduit about its vertical axis for each rotation of said nozzle member about its horizontal axis.

2. A device for cleaning tanks and the like 75 embodying: a vertical feed pipe; a sleeve rotat-

ably mounted on the lower end of said pipe; a horizontally extending nozzle feed pipe angularly mounted on said sleeve; a reaction nozzle member rotatably mounted on said nozzle feed pipe; means operable by the rotation of said nozzle member for intermittently turning said sleeve member on said vertical pipe. 8

3. A device for cleaning tanks and the like embodying: a main feed pipe; a sleeve rotatably mounted on the lower end of said main feed pipe; 10 a ratchet wheel rigidly mounted on said main feed pipe above said sleeve; a bracket on said sleeve below said ratchet wheel; a pawl member on said bracket with one end engaging said ratchet; a nozzle member mounted on said sleeve 15 for rotation about a horizontal axis; a nozzle on said nozzle member arranged so as to rotate said nozzle member during the passage of a pressure fluid therethrough; and means operated by the rotation of said nozzle member for moving said 20 pawl member relative to the teeth on said ratchet wheel.

4. A device for cleaning tanks and the like embodying: a main feed pipe; a sleeve rotatably mounted on the lower end of said main feed pipe; 25 a ratchet wheel rigidly mounted on said main feed pipe above said sleeve; a bracket on said sleeve below said ratchet wheel; a bell crank; yieldable means securing said bell crank to said bracket with one arm engaging said ratchet 30 wheel; a T member on the lower end of said sleeve; a nozzle feed pipe in said T member; a reaction nozzle member rotatably mounted on said nozzle feed pipe; a shaft extending through said T member; means for rotating said shaft 35 from said nozzle; an eccentric on said shaft; and a pitman rod connecting said eccentric with said bell crank.

5. A device for cleaning tanks and the like embodying: a main feed pipe; a sleeve rotatably 40 mounted on the lower end of said main feed pipe; a ratchet wheel rigidly mounted on said main feed pipe above said sleeve; a bracket on said sleeve below said ratchet wheel; a bell crank; yieldable means securing said bell crank to said bracket 45 with one arm engaging said ratchet wheel; a T member on the lower end of said sleeve; a nozzle feed pipe in said T member; a reaction nozzle member rotatably mounted on said nozzle feed pipe; a shaft extending through said T member; 50 means for rotating said shaft from said nozzle; an eccentric on the end of said shaft; a pitman rod connecting said eccentric with said bell crank; another eccentric formed on said shaft on the axis of said sleeve; a collar on said last mentioned eccentric; and an indicator shaft extending 55 upwardly through said sleeve and said main feed pipe, said indicator shaft having a projecting end exposed above the top of said main feed pipe. 60

6. A device for cleaning tanks and the like embodying: a main feed pipe; a sleeve rotatably mounted on the lower end of said main feed pipe; a ratchet wheel rigidly mounted on said main feed pipe above said sleeve; bearing brackets on said sleeve; a shaft rotatably mounted in said bearing brackets in substantially parallel relation with said sleeve; an eccentric on the upper end of said shaft; a pawl on said eccentric with its free end engaging said ratchet wheel; and means for rotating said shaft so as to reciprocate said pawl relative to the teeth on said ratchet wheel, said last mentioned means comprising a pinion on the lower end of said shaft, a reaction nozzle mounted for rotation about a substantially horizontal axis 70 75 80 85 90 95 98

on the lower end of said sleeve, and gear means driven by said nozzle and engaging the pinion on said shaft.

7. A liquid spray of the class described embodying: a fixed conduit; a rotatable conduit mounted on said fixed conduit in coaxial relation therewith; a nozzle member mounted on said rotatable conduit for rotation about an axis which is normal to the axis of said fixed and rotatable conduits; and means extending into the path of the nozzles and operable by the rotation of said nozzle member for turning said rotatable conduit step by step about its axis, said conduits and said nozzle member all being in internal communication with each other and said nozzle member having tips arranged to propel the same during the passage of liquid therethrough.

8. A device for cleaning tanks and the like embodying: a main feed pipe adapted to extend through the manhole of the tank and vertically therebelow; a sleeve rotatably mounted on the lower end of said pipe; a nozzle feed pipe angularly mounted on said sleeve; a nozzle member rotatably mounted on said nozzle feed pipe; a nozzle on said nozzle member arranged so as to rotate said nozzle member during the flow of a pressure fluid therethrough; and means including a member engaging said nozzle and adapted to rotate therewith for imparting step by step turning movement to said sleeve from said pipe.

9. A device for cleaning tanks and the like embodying: a vertical main feed pipe; a sleeve rotatably mounted on the lower end of said main feed pipe; a horizontally extending nozzle feed pipe mounted on said sleeve; a nozzle member rotatably mounted on said nozzle feed pipe; reaction nozzles on said nozzle member; means operated by said nozzle member for turning said sleeve on said vertical pipe; and a conical ring

surrounding said main feed pipe and positioned a substantial distance above said nozzle member for angularly deflecting a part of the liquid stream projected upwardly from said nozzle member.

10. A device for cleaning tanks and the like embodying: a conduit; means for rotatably suspending said conduit on a substantially vertical axis; a nozzle member mounted on said conduit in internal communication therewith for rotation about a horizontal axis; means for delivering a pressure liquid into said conduit for projection from said nozzle member; means operated by said pressure liquid for rotating said nozzle member about its horizontal axis; and means operable during the rotation of said nozzle member about its horizontal axis for automatically imparting one step of rotation to said conduit about its vertical axis for each rotation of said nozzle member about its horizontal axis.

11. A device for cleaning tanks and the like embodying: a vertical feed pipe, a sleeve rotatably mounted on the lower end of said feed pipe, a horizontal nozzle feed pipe mounted on said sleeve, a nozzle member rotatably mounted on said nozzle feed pipe, said nozzle being so constructed as to deliver a substantially compact stream, means for continuously rotating said nozzle member, and means operable by the rotative movement of said nozzle member for intermittently turning said sleeve member on said vertical pipe while discharging said stream to sweep the wall of said tank in successive defined paths, said turning movement being in an amount such as to produce overlapping of the paths of said streams upon successive rotative movements of said nozzle.

CLARE RICHARD.
HAROLD M. RUTH.
